G. E. MATHER,
TELEPHONE RECEIVER,
APPLICATION FILED JULY 9, 1917.

1,279,894.

Patented Sept. 24, 1918.

Inventor:
George E. Mather.
by *J. E. Roberts* Atty.

UNITED STATES PATENT OFFICE.

GEORGE E. MATHER, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE-RECEIVER.

1,279,894.

Specification of Letters Patent. Patented Sept. 24, 1918.

Application filed July 9, 1917. Serial No. 179,424.

To all whom it may concern:

Be it known that I, GEORGE E. MATHER, a citizen of the United States, residing at East Orange, in the county of Essex and 5 State of New Jersey, have invented certain new and useful Improvements in Telephone- Receivers, of which the following is a full, clear, concise, and exact description.

This invention relates to the adjustment 10 of vibratory diaphragms, and more particularly to the adjustment of diaphragms of telephone receivers and the like relative to another part of such apparatus.

The object of the invention is to provide a 15 simple, economical and efficient means to admit of a rapid adjustment of a diaphragm in relation to another part of the apparatus. To accomplish this object, the diaphragm is secured to a cap by suitable clamping means; 20 the cap being adjusted on a casing and springs located in suitable grooves, serving to frictionally engage another part of the apparatus to hold the cap and casing in any desired adjusted position. This serves to 25 space the diaphragm, carried by the cap, a suitable distance from the casing and the parts carried thereby.

The drawing illustrates an exploded view 30 of the invention as applied to a telephone receiver designed for use as a "howler" in train despatching work.

A magnet casing 1 is provided and externally screw-threaded at its upper end to receive a cap internally screw-threaded and 35 provided with a smooth seat for a diaphragm 3. The cap 2 carries a horn 4 to concentrate the sound waves emitting from the diaphragm during operation of the "howler." The diaphragm 3 is held in the 40 cap 2 by a screw-threaded clamping ring 5, which is positioned within the cap to hold the diaphragm in place; spanner grooves 6 being provided to facilitate movement of the ring. The inner side of the ring 5 has a 45 number of grooves 7 in which are fastened U-shaped leaf springs 8, one leg of each spring being secured at one end to the bottom of its groove 7, while the other leg thereof normally extends a considerable distance above the inner surface of the ring 50 to engage the upper edge 9 of the casing 1.

The casing 1 has a pair of receiver magnets 10 mounted therein, and to determine the proper air gap between the diaphragm

3 and the magnets 10, the cap 2 is screwed 55 on the casing 1 and adjusted back and forth until the most satisfactory operating position is found, whereupon the friction present between the springs 8 and the top 9 of the casing 1 will hold the parts in this position. 60 The springs 7 serve to take up the back lash of the screw threads at all times and obviate the possibility of destroying the preliminary adjustment; a trouble experienced heretofore where locking rings have been used as 65 turning of the ring to lock the cap and casing in adjusted position often resulted in moving the diaphragm away from the casing and destroying the preliminary adjustment. By locating the springs 8 in the recess 7, a greater range of adjustment is possible, since the springs can be forced down without injury to any of the parts until the ring 5 engages the top 9 of the casing. To 70 prevent possible injury to the diaphragm the parts of the receiver are preferably so proportioned that the diaphragm will not be forced against the ends of the magnets 10 even though the cap 2 be adjusted to bring the ring 5 into engagement with the top 9 of the casing. By using U-shaped leaf 75 springs, a greater area of contact is provided between the upper edge of the casing and permits of smoother operation during adjustment.

85 This arrangement, while especially suitable for receivers wherein it is desired to adjust the air gap between the receiver magnet and diaphragm, may also be used in a variety of other places where it is desired to 90 provide adjustment between a vibratory diaphragm and some other part of the apparatus.

What is claimed is:

1. A diaphragm adjustment for telephones and the like comprising a casing member, a cap member, one of said members having a notch therein, means to provide adjustment between said members, a diaphragm carried by one of said members and 95 movable therewith, and a U-shaped spring positioned in said notch, one end of said spring being secured to the bottom of said notch and the other end of said spring engaging said other member to hold said members in adjusted positions.

100 2. A diaphragm adjustment for telephones and the like comprising a casing

member, a cap member, a diaphragm carried by said cap member, means for holding said diaphragm in said cap member, said means having a notch therein, and a U-shaped spring secured in said notch adapted to engage said casing member and hold said members in adjusted position.

3. A diaphragm for telephones and the like comprising a casing member having an open end, a cap for said casing member, a diaphragm carried by said cap, an annular member for retaining said diaphragm in said cap, said annular member having a rectangular shaped notch therein, and a U-shaped spring mounted in said notch, one end of said spring being secured to the bottom of said notch and the other end extending beyond said annular member to engage

the open end of said casing to hold said cap and casing in adjusted position.

4. A diaphragm adjustment for telephones and the like comprising a casing member, a cap member, a diaphragm carried by said cap member, means to hold said diaphragm in place, a U-shaped spring adapted to engage said members and hold them in adjustment, one of said members having a notch therein in which said spring is secured, said notch being sufficiently deep to completely house said spring to avoid its interference with the adjustment of said members.

In witness whereof, I hereunto subscribe my name this 5th day of July A. D., 1917.

GEORGE E. MATHER.
